FIG. 1 is a perspective view of a handle for a draw bar of a

luggage case showing my new design;

FIG. 2 is a front elevational view thereof;

FIG. 3 is a rear elevational view thereof;

FIG. 4 is a right side elevational view, a left side elevational
view being a mirror image thereof;

FIG. 5 is a top plan view thereof;

FIG. 6 is a bottom plan view thereof; and,

FIG. 7 is a perspective view from the bottom.

The broken lines are shown for illustrative purposes only and
form no part of claimed design.
